FRICITION REVERSE ATTACHMENT

Filed Aug. 23, 1928

W. J. Edwards.
INVENTOR.

BY *Ernest L. Hood*
ATTORNEY.

UNITED STATES PATENT OFFICE

WILLIAM J. EDWARDS, OF WICHITA FALLS, TEXAS, ASSIGNOR TO CLARK MACHINE COMPANY, OF WICHITA FALLS, TEXAS

FRICITION REVERSE ATTACHMENT

Application filed August 23, 1928. Serial No. 301,664.

This invention relates to oil field machinery, especially combination well drilling and clean-out machines, and the invention refers particularly to an improved friction reverse attachment for such machines, the principal object being to provide an attachment as specified, capable of reversing the direction of rotation of the drilling drum or casing drum from the drive shaft, with speed and readiness in setting up casing and pulling pipe and in other instances where reversibility of these drums is desired.

Another object of the invention resides in the provision of an arrangement so disposed on the drive shaft as to be alternately operative, that is to say, will bring about frictional engagement between the drive shaft friction pulley and drilling drum wheel in one position, and between the said friction pulley and casing drum in another position, the alternate positions thereof being obtained through a single operating lever.

Still another object of the invention resides in the provision of a double lever arrangement by which the rotative action of the said drums may be controlled either individually or in unison.

With the foregoing objects as paramount, the invention has especial reference to its salient features of construction and arrangement of parts to become manifest as the description proceeds, taken in connection with the accompanying drawings wherein:—

Figure 1 represents a side elevational view of a combination well drilling and clean-out machine showing the invention in operative position thereon.

Figure 2 is a fragmentary plan view of the machine and the invention.

Figure 3 is a detail view of a modified form of the invention, showing its adaptability in controlling the movements of both the drums.

Figure 4 is a detail view of one of the pulleys by which the rotative motion of the friction drive is transferred to the drum wheels.

The machine for which the invention has been designed, being of conventional and well known manufacture in its art, no detailed ex-

planation is considered necessary in order to demonstrate the relative association between its parts and the invention. Consequently, only those parts directly affected by the operation of the invention will be referred to hereinafter and identified by characters of reference.

Accordingly, 1 designates the frame of the machine upon which is arranged the large band wheel 2, operating the walking beam 3 through pitman 4 in the conventional manner. A folding mast 5 is shown at the left in Figure 1, a portion of which is broken away as apparent.

Arranged upon the frame 1 in parallel relationship are the casing drum and drilling drum shafts 6 and 7 respectively, upon which the drums 8 and 9 are mounted, shown only in Figure 2.

Intermediate the drum shafts 6 and 7 is arranged the common drive shaft 10, carrying pinions 11 and 12 which enmesh the gears 13 and 14 carried by drums 8 and 9 respectively. The position of the pinions 11 and 12 shown in Figure 2 is the neutral position, being in engagement with neither of the gears 13 and 14, it being understood that they may be moved longitudinally on the drive shaft 10 to effect alternate engagement between the pinions and gears in imparting rotative motion to either of the drums 8 and 9.

Suitable lever connections are established between the pinions 11 and 12 and the operator's position at the machine, and since these connections form no part of the invention, they have not been illustrated.

At the side of the machine frame 1, on the end of shaft 10 is arranged a drive chain 15, as also apparent in Figure 2, transmitting driving power to the shaft 10, from a source of power (not shown).

From the foregoing, it is apparent that as the drive shaft 10 is driven in a clockwise direction, with pinion 11 operatively engaging large gear 13, casing drum 8 will be revolved in an anti-clockwise direction to wind or unwind the line thereon in setting up or breaking out casing.

In drilling operations, the pinions are

shifted on shaft 10 to bring pinion 12 into operative engagement with drilling drum gear 14, the casing drum 8 being in the meantime held by the conventional brake band 16. Consequently, by so shifting the pinions, driving power is shifted to the drilling drum 9.

Referring now especially to the invention and its relationship with the above mentioned conventional parts of the machine it may be here stated that the invention is primarily intended to be used principally on the casing drum 8 for running blocks up and down in setting or pulling pipe.

On one end of each of the drum shafts 6 and 7 is mounted one of pulleys 17 and 18 respectively, which are substantially the same size, and upon the protruding end of the drive shaft 10, intermediate the pulleys 17 and 18 is mounted a pulley 19 of a suitable composition such as paper, to supply maximum friction. This friction pulley, being fixed to the shaft 10 of course rotates in the same direction as the shaft 10.

A reversing mechanism comprising a rockable member 22 is loosely mounted on the power shaft 10 and has a pair of divergent arms 20 which latter have rollers 21 journaled thereon, the arms being rigidly connected to the member 22, the latter being operated by a rod 24 which is pivoted to the member and to a hand lever 27, mounted upon a shaft 26, whereby upon operation of the lever 27 the rockable member will be actuated as shown in the drawings.

In practical operation of the invention, and assuming that the machine is engaged in setting up casing, with reference to Figure 3, as the casing is lowered into the well, the line is unwound from the drum 8 and in raising the blocks and rewinding the line, it is simply required to exert a pull upon the lever 27, causing one of the rollers 21 to engage the drum pulley 17, causing the two shafts 6 and 10 to rotate in the same direction. Obviously, this arrangement dispenses with the necessity of having to reverse the engine when setting up or breaking out casing, thus prolonging not only the usefulness of the engine but also the moving parts of the machine.

The foregoing description applies also to the control of the drum 9 in drilling operations, in winding and unwinding the line on the drum when using cable tools.

Manifestly, the construction shown may be capable of some structural alterations to suit varied requirements, and such modifications as may be considered within the scope of the appended claim are also considered within the spirit of the invention.

I claim:

In combination with a well drilling apparatus having a pair of drums and a power shaft therebetween, a reversing mecha-

nism comprising a rockable member loosely mounted on said power shaft, a pair of spaced friction rollers carried by said rockable member, each of said rollers being disposed between the power shaft and one of the drums, and means for manually actuating the rockable member whereby each of the rollers is moved into and out of operative engagement with the power shaft and its adjacent drum.

In testimony whereof I affix my signature.

WILLIAM J. EDWARDS.
